UNITED STATES PATENT OFFICE.

HARVEY HUBBELL, OF BRIDGEPORT, CONNECTICUT.

KEY-SOCKET.

No. 878,633.

Specification of Letters Patent.

Patented Feb. 11, 1908.

Application filed March 5, 1907. Serial No. 360,785.

To all whom it may concern:

Be it known that I, HARVEY HUBBELL, a citizen of the United States, residing at Bridgeport, county of Fairfield, State of Connecticut, have invented a new and useful Key-Socket, of which the following is a specification.

This invention has for its object to produce a single-pole key socket which shall be inexpensive to make, perfectly certain and safe in use and practically impossible to get out of repair. With these ends in view I have devised the novel key socket which I will now describe, referring to the accompanying drawing forming a part of this specification and using reference characters to indicate the several parts.

Figure 1 is an elevation of the socket, the shell being in section; Fig. 2 an elevation of the socket detached, from a point of view directly opposite to that in Fig. 1; Fig. 3 a longitudinal section on the line 3—3 in Fig. 2, looking in the direction of the arrows; Fig. 4 an inverted plan view corresponding with Fig. 2; Fig. 5 a detail elevation corresponding with Fig. 1, the contact plate and operating plate being removed and the shaft in section; and Fig. 6 is a detail view showing the end of the shaft or key, with the contact plate, contact springs and the operating plate in side elevation.

10 denotes the shell, 11 the insulating block, 12 the socket proper which receives the base of a lamp and 13 the shaft or key which passes through the insulating block and is provided with an insulating finger-piece 14 shown as provided with a shank 15.

16 and 17 denote the binding screws. Binding screw 16 passes through a plate 18 and engages the insulating block, a recess 19 being provided in the insulating block for the plate and the plate being secured to the insulating block by the screw. The shaft passes through a hole 20 in plate 18, fitting 45 the hole closely. The current passes from the plate to the shaft which may or may not be bushed in the hole.

21 denotes a spring surrounding the shaft and bearing against plate 18 and against the 50 inner end of the shank of the finger-piece. Binding screw 17 passes through a plate 22 lying in a groove 23 in the insulating block and secures said plate to the block. One of the wires (not shown) passes through this 55 groove to the binding screw. A groove 24 is also provided in the insulating block

through which the other wire (not shown) passes to binding screw 16. The lower end of plate 22 is curved inward, passes through a recess 25 in the socket and lies in a recess 26 in the bottom of the insulating block. A screw 27 passing through the insulating block engages this plate. The inner end of plate 22 lies at the center of the underside of the insulating block and forms one of the 65 contacts with a lamp base (not shown). The upper end of socket 12 is provided with an inwardly-turned flange 28 which lies in recess 26 and is secured to the insulating block by screws 29 and 30, which pass 70 through the block. This flange provides the other contact with a lamp base (not shown).

31 denotes a recess in the insulating block directly opposite to recess 19. At the base of this recess are four inclines 32 which terminate in abrupt shoulders 33.

34 denotes the contact plate which is provided with a central hole 35 through which the shaft passes freely, with two contact springs 36 which are formed from the metal of the plate and are downwardly turned to engage the inclines at the bottom of the recess, and with two stops 37 which may be formed by punching out curved tongues of metal from the plate, leaving one end of each tongue attached to the plate and springing the free end downward. The shoulders are engaged by the ends of the contact springs and act to prevent the contact plate from being turned backward. The end of the 90 shaft is made angular, as at 38, to receive a corresponding opening in an operating plate 39 which is carried thereby, the plate being secured in place upon the shaft by a pin 40 or in any suitable manner. The operating 95 plate is provided with two downwardly extending lugs 41 which are adapted to engage two stops 37 on the contact plate and are retained in contact therewith by spring 21. These lugs may be formed by cutting out 100 circular tongues of metal from the operating plate, leaving one end of each tongue attached and bending the free end downward.

42 denotes a plate in the circuit which covers one of the inclines 32 and is provided with an inwardly-turned end 43 which lies in contact with the inwardly-turned flange 28 of socket 12 and is retained in place by screw 30 which passes through it.

The two lugs 41 and the two stops 37 constitute engaging members which can only co-act to advance the contact springs when

the shaft is in one of two diametrically opposite positions. In other words, the said lugs and stops are relatively arranged so that, although the shaft can be rotated backward 5 without imparting movement to the contact plate, forward rotation of the shaft will cause engagement with the contact plate only when the key is turned half way around. Consequently, the key and shaft can only be 10 employed to switch the current on and off when the key is in its proper prearranged position relatively to the contact plate to insure an indication by the key whether the shaft and contact plate are in position to complete or break the circuit, thereby permitting 15 the key to indicate, in substantially the same manner that a gas key does, whether the current is on or off.

The operation is as follows: Starting for 20 convenience with binding screw 17, the current passes through plate 22 to the lamp, thence back through flange 28, plate 42, the contact springs and contact plate to the shaft and from the shaft through plate 18 to binding screw 16. As there are two contact 25 springs, one plate in the circuit engaged by said springs and four inclines engaged by said springs, including the one covered by the plate, it follows that each quarter turn of the 30 shaft or key will close or open the circuit and light or extinguish a lamp. When either of the contact springs is in engagement with plate 42, the circuit will be closed and the lamp lighted, the other contact spring being 35 in engagement with the incline opposite to the one covered by the plate. A quarter turn of the shaft will carry the contact springs past shoulders 33 and they will drop down upon the inclines intermediate the inclines previously engaged, thus breaking the 40 circuit and extinguishing the lamp. Another quarter turn of the shaft will place the contact spring which was previously out of engagement with plate 42 in engagement with said plate and will again close the circuit and 45 light the lamp. These movements may be continued indefinitely, each quarter rotation forward of the shaft acting to alternately light and extinguish the lamp. The contact 50 plate is carried forward through the engagement of lugs 41 on the operating plate with stops 37 on the contact plate. When the shaft is turned backward, however, lugs 41 thereon will ride backward over the contact 55 plate but without imparting movement thereto, it being harmless to the switch to turn the shaft backward without limit. Spring 21 acts to retain the lugs in close engagement with the contact plate and as soon as the 60 shaft is turned forward the lugs will again engage the stops and carry the contact plate forward.

Having thus described my invention I claim:

1. A key socket comprising an insulating block having a recess with inclines at its base, a plate in the circuit covering one of said inclines, a shaft and a contact plate carried forward by the shaft and having contact springs engaging opposite inclines, so that each quarter turn of the shaft will alternately open and close the circuit, the connection between the shaft and contact plate having operative engaging means which 70 coact to permit advance of the contact plate only when the shaft is in one of two diametrically opposite positions relatively to said plate. 75

2. A key socket comprising an insulating block having a recess with a plurality of inclines at its base, a plate in the circuit covering one of said inclines, a shaft, a contact plate through which the shaft passes and which is provided with two stops and two contact springs engaging opposite inclines 80 and an operating plate carried by the shaft and having two lugs engaging the stops and carrying the contact plate when the shaft is turned forward, said lugs passing backward over the contact plate when the shaft is 85 turned backward. 90

3. A key socket comprising an insulating block having a recess with four inclines at its base, a plate in the circuit covering one of said inclines, a shaft, a contact plate through which 95 the shaft passes and which is provided with two contact springs engaging opposite inclines and with two stops, an operating plate having two lugs engaging the stops when the shaft is turned forward and moving 100 backward over the contact plate and a spring acting to retain the operating plate in engagement with the contact plate and the contact springs in engagement with the inclines. 105

4. A key socket comprising an insulating block having a recess with inclines at its base each terminating in a shoulder, for the purpose set forth, a plate in the circuit covering one of said inclines, a shaft, a contact plate through which the shaft passes and which is provided with contact springs engaging opposite inclines and with stops, an operating plate carried by the shaft and having lugs engaging the stops when the shaft is 110 turned forward and passing backward over the contact plate, means for retaining said plates in engagement and the contact springs in engagement with the inclines, and means for advancing the contact plate only when the shaft is in one of two diametrically opposite positions relatively to said plate. 115 120

In testimony whereof I affix my signature, in presence of two witnesses.

HARVEY HUBBELL.
